UNITED STATES PATENT OFFICE.

FRANK GLENN RUGH, OF BRIAR BLUFF, ILLINOIS, ASSIGNOR OF ONE-FOURTH TO WILSON W. ADAMS, OF ATKINSON, ILLINOIS.

TELEPHONE SYSTEM.

SPECIFICATION forming part of Letters Patent No. 656,703, dated August 28, 1900.

Application filed June 28, 1899. Serial No. 722,172. (No model.)

To all whom it may concern:

Be it known that I, FRANK GLENN RUGH, a citizen of the United States, residing at Briar Bluff, in the county of Henry and State of Illinois, have invented certain new and useful Improvements in Telephone Systems; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This invention relates to a telephone system, by the use of which any one station or subscriber on a line containing three or more instruments may be called up without the call being rung at the remaining stations, which latter being cut out of the calling circuit will remain quiet.

It is well known that on telephone-lines in which three or more instruments are in circuit when one subscriber is called the bells of all the instruments on the circuit ring at the same time, giving general warning that some one is about to talk over the line. Great annoyance is occasioned by this general signaling, as persons at the uncalled stations will often remove their telephones from the hooks and listen to the conversation passing over the line. Besides the annoyance of having their conversation overheard the subscribers fail to get the best service, as the interfering parties ground the line when they remove their receivers from the hooks, which, shunting in a low resistance, interferes with and prevents conversation between persons separated a considerable distance from each other.

The object of my invention therefore is to overcome this defect and so improve the service that on lines including three or more instruments in circuit any subscriber on the line may call any other subscriber without informing others of the fact. This object I accomplish by such combination and adjustment of the parts and the advantageous connections at the instruments that normally all the telephones except one, usually the last called, are cut out of the line. By this arrangement when one subscriber wishes to talk

to another he first brings the desired instrument onto the line through means hereinafter described, at the same time automatically cutting out the one previously on the line. 55 After this the caller turns his magneto-generator in the usual manner and rings the bell at the desired station. All other instruments being off the line, their bells cannot ring, so no one other than the person called is aware 60 that the line is in use. This arrangement also permits several lines to be coupled up, making one long circuit, over which conversation can be carried on with facility and secrecy. 65

In the accompanying drawings, Figure 1 is a diagrammatic view of a telephone-circuit consisting of three stations, showing one arrangement of my invention. Fig. 2 is a similar view of a modified arrangement of the invention. Figs. 3 and 4 are detail views of the mechanism for bringing the telephones onto the line.

The arrangement of system illustrated in Fig. 1 shows three stations (indicated by the numerals 1, 2, and 3) connected by the line-wires *a* and *b*, the former wire being an open-circuit wire when the instruments are not in use, while the wire *b* is a closed-circuit one, the current passing from battery *X* by way 70 of said wire through the several stations in turn, then to earth, and back to battery. While I have shown but three instruments on the line, any number up to twenty or thirty may be conveniently placed thereon. 75 Each station is provided with a disk *D*, mounted on a shaft adapted to be rotated by suitable means in the direction of the arrow and controlled in its rotation by a lever *L*, drawn in one direction by an electromagnet *M* and 80 in the opposite direction by a spring *N*. The main-line wire *b* is connected at each station to the electromagnet *M* and also to a normally-closed circuit-breaker or key *K*, the latter being used to open and close the circuit 85 when the disks *D* are to be rotated for calling up a station by closing the circuit through line-wire *a* at that station. On the face of each disk *D* is a series of numerals, each numeral representing a station on the line. 90 Fixed to each disk at its respective station-number is a pin *p*, adapted to close connec-

tion between a pair of spring-fingers S or other circuit-closing device in the main line a. The circuit-closing fingers S are so arranged with relation to the numerals on their approximate disks that when any number—say “1”—at one station is beneath the circuit-closing fingers the same number on the disks at all the other stations will be in similar position. The pins p, however, being placed opposite a different number at each station, it follows that no two stations can be cut in at the same time. When one of the keys K is operated, the circuit through the main line b, ground E, and battery X is causing all the levers L to vibrate and the several disks to move synchronously in the direction of the arrow. To one of the fingers S of the circuit-closing fingers S at each station is attached a wire c, which is connected to the magnet of a signal-bell B, and thence passes to and is attached to a contact point or stop e beneath the telephone-hook H, which connects therewith when the receiver is hung on said hook. A wire h passes from the hook H to ground. 15 A shunt-wire d at each station is connected to the spring-finger S' and passes thence to a magneto-generator G, being attached to a normally-open contact d', which is automatically closed in the well-known manner when the generator is operated. A wire d² connects the armature of the generator G to the telephone-hook H. At each station the ordinary telephone-hook H is raised by means of a spring into contact with two contact points 20 or stops f and g when the telephone or receiver is removed; but when it is hung thereon it (the hook) is drawn down into contact with the stop e, heretofore described. From the stop f a wire i passes to one end of the 25 primary winding of an induction-coil I, and a wire i' connects one end of the secondary winding of the coil to the same stop f. The opposite end of the primary winding of the induction-coil is connected by a wire t to a battery 30 x, transmitting-telephone T, and the stop g. The other end of the secondary winding of the induction-coil is attached to a receiving-telephone R by means of a wire r, which extends thence to the shunt-wire d, connected, 35 as heretofore described, to the main-line wire a. 40 The operation of the system above described is as follows: Suppose the subscriber at station 1 desires to call up station 3. He must first operate his key K, which will open and close the circuit through the main-line wire b, magnets M, battery X, and earth. This will cause all the disks on the line, be there 45 three or thirty, to move synchronously. When the numeral “3” on the disk of the calling station reaches a position beneath the circuit-closer S, the operator, knowing that the pin p on the disk at station 3 has brought the fingers s' of circuit-closer S into contact, removes his finger from the key and turns his generator. The circuit through the generator 50 being automatically closed by this operation,

the current passes from the generator by way of the wire a and main-line wire a to circuit-closer S of station 3, thence by wire c through bell B to telephone-hook H and by wire h to ground, returning to station 1, up wire h to telephone-hook, and by way of wire d² back to generator. The subscriber at station 3 hearing his bell ring removes his receiver R 75 from the hook H and calls station 1, who in the meantime has removed his receiver from its hook H, and they proceed to talk. Each transmitting-telephone is in an independent circuit formed by a battery x, primary winding of the local induction-coil I, wire i, stops f g, telephone-hook H, and wire t. The receiving-telephone R is in the secondary circuit of the active induction-coils I, the current of which passes from the coil by wire r 80 through the receiver R to wire d and main-line wire a to station 3, thence by wires d and r of said station 3 through receiver R to the secondary winding of coil I, wire i', to stop f, telephone-hook H, which had been drawn into 85 contact with stop f and g when the receiver R was removed, and wire h to ground, back to station 1 and by way of wire h, telephone-hook H, stop f, and wire i' to coil I. The receivers R having been removed from their 90 hooks H, the latter are drawn up by their springs, breaking the circuit through the bell at the stop e and closing the circuits through the transmitters T and receivers R by connecting the stops f and g. The circuit-closers 95 S of all other instruments except at station 3 being open and no other bell than that at station 3 being sounded, the other subscribers on the line will not know that the line is being used. Hence they will not take their receivers off the hooks H. 100

The secondary circuit, which contains the receivers R, is, as hereinbefore described, a ground-circuit; but by omitting the ground-wire h and connecting each hook H to the 105 main-line wire b, as shown by the dotted lines L, a metallic circuit is formed.

The disk D, on the face of which the various station-numbers are placed and to which the pin p is attached, is secured to a shaft D', (see Figs. 3 and 4,) adapted to be rotated by any suitable clock mechanism. An escapement-wheel D² on the shaft D' is engaged by pallets D⁴ on the arm L, to which an armature D³ is attached. The lever L, heretofore described, is moved in opposite directions or vibrated by the alternate action of the electromagnet M and spring N. Each movement of the lever L allows the escapement-wheel D² to turn the distance of one tooth, which will gradually and intermittently bring the pin p on the disk D into position to close the circuit-closer S. 115

The modified form of my telephone system illustrated in Fig. 2 differs in some respects from the form shown in Fig. 1. In the system shown in Fig. 2 I use but one battery for all purposes—that is to say, for bringing a station onto the line a, ringing the bell, and 120

vitalizing the primary circuit of the induction-coils. A circuit-changer C is introduced into the main-line circuit b at each station for shunting the current around the magnets M and through the signal-bell B. To each telephone-hook H an insulated plate j is attached to its upper side and a similar plate k secured to its under side. Contact points or stops m n are so placed that when the receiver R is removed from the hook H a spring will lift the hook and bring the insulated plate into electrical connection with said contact-points m n. The same movement will close a circuit between the hook H and a contact-point o. The weight of the receiver when on the hook breaks connection with the contact-points m, n, and o and lowers the hook into contact with the stop e. The stops p g are by the same movement electrically connected by the insulated plate k. The circuits are as follows: To call up station 1 from station 3, the key K at station 3 is operated until the disk D indicates that the pin p at station 1 has closed the fingers of circuit-closer S. As in Fig. 1, the main-line circuit b is a closed circuit passing from battery X by wire b to stop q beneath the hook H, insulated plate k, stop p, again on wire b, through the key K and circuit-changer C at station 3 to the main-line wire b, which enters station 2, and, passing over a similar route therein, as in station 3, continues to station 1, where after again passing through the instrument in a similar manner it goes to ground and back to station 3. After having cut in station 1 the operator at station 3 presses his circuit-changer C into contact with point a², shunting the current around the magnet M and by way of wire a' and main-line wire a to finger S of the circuit-closer at station 1 without passing through the instrument at station 2. When the current reaches station 1, it passes through the circuit-closer S to bell B by wire c, thence to stop e, telephone-hook H to ground and back to battery, causing bell B at station 1 to ring until the circuit-changer C at station 3 is released. When the finger has been removed from the circuit-changer C and the receivers taken from their hooks H, the said hooks are lifted immediately into contact with the points m, n, and o. While the persons at each station are talking, the primary circuit is from the battery X by wires b t through transmitter to the primary winding of the induction-coil I at station 3, from whence it passes by wire i to stop n, across the insulated plate j to stop m, and by wire b³ to main-line wire b, out of station 3 to stations 2 and 1 in succession, through which the circuit passes in a similar manner, as in station 3. After passing through station 1 the circuit is completed through the ground to battery X. By this arrangement the primary circuit passes through the two transmitters in use on the line. The secondary circuit is readily traced from the secondary winding of the induction-coil at station 3 through the receiver R by way of wire r to main-line wire a, running directly to station 1, thence through wire r at that station, receiver R, secondary winding of induction-coil I, wire i' to stop o, thence over the hook H, wire h to ground, back to station 3, and by wire h, hook H, stop o, and wire i to induction-coil I, from whence it started. The advantage in this arrangement over that now in use consists in having one battery only to generate all the energy necessary for the entire line, thus doing away with local batteries and magneto-generators and bells at each station, an ordinary electric bell being substituted for the magneto-bell now in use. The battery being at the central station or at one end, it can be cared for and kept in order more readily than when subdivided into local batteries.

Having thus described my invention, I claim—

1. In a telephone system, a normally-closed main circuit, a normally-open main circuit and a plurality of stations thereon, in combination with a signal at each station on the normally-open circuit, a telephone-receiver and an induction-coil in a shunt from the normally-open circuit at each station, a circuit containing a telephone-transmitter passing through the primary winding of each induction-coil, a selective mechanism and a circuit-breaker on the normally-closed circuit at each station, and a source of electrical energy, substantially as described.
2. In combination with a rotatable disk, an escapement mechanism operated by an electromagnet for rotating said disk, a normally-closed circuit passing through the electromagnet, a circuit-breaker in the normally-closed circuit, a normally-open circuit containing a signal-bell and adapted to be closed by the rotary movement of the disk, an induction-coil, a telephone-receiver and the secondary winding of the induction-coil in a shunt from the normally-open circuit, a telephone-transmitter and the primary winding of the induction-coil in a local circuit, and a source of electrical energy, substantially as described.
3. The combination of a normally-closed electric circuit, a series of telephone-stations each containing a selective mechanism on the said circuit, a normally-open electric circuit, a series of circuit-closers on the open circuit adapted to be closed each by one of the selective mechanisms, a shunt-circuit from the closed circuit through a telephone-transmitter and the primary winding of an induction-coil at each station, a shunt-circuit from the closed circuit to the open circuit around each selective mechanism, a signal-bell circuit at each station adapted to form a part of the main open circuit, and a battery for furnishing energy to the several circuits.
4. A telephone system having a plurality of stations, a normally-closed circuit and a normally-open circuit passing through said stations, a selective mechanism on the closed

circuit at each station, a circuit-breaker or key also on the closed circuit at each station for operating the several selective mechanisms, a circuit-closer at each station operated by the selective mechanism for closing the normally-open circuit, a signal-bell at each station and a generator in the normally-open circuit, an induction-coil at each station, a telephone-transmitter and a battery in circuit 10 with the primary winding of each induction-

coil, a telephone-receiver and the secondary winding of each induction-coil in a shunt from the normally-open circuit, and a battery, substantially as described.

In testimony whereof I affix my signature 15 in presence of two witnesses.

FRANK GLENN RUGII.
